UNITED STATES PATENT OFFICE.

FRANCIS H. STILLMAN, OF NEW YORK, N. Y.

HYDRAULIC JACK.

SPECIFICATION forming part of Letters Patent No. 757,512, dated April 19, 1904.

Application filed November 8, 1902. Serial No. 130,505. (No model.)

To all whom it may concern:

Be it known that I, FRANCIS H. STILLMAN, a citizen of the United States, and a resident of Brooklyn, in the county of Kings, in the city 5 and State of New York, have invented a certain new and useful Improvement in Hydraulic Jacks, of which the following is a full, clear, and exact description, reference being made to the accompanying drawings, forming part of 10 this specification.

This invention relates to improvements in means to prevent the generation of excessive pressure in hydraulic jacks when heavy objects are quickly lowered with them; and the 15 invention consists of a hydraulic jack having at the top of the fluid-reservoir the capillary vent hereinafter described, and defined in the claims.

On the accompanying sheet of drawings, 20 Figure 1 is a sectional elevation of a fragment of a jack embodying the invention; Fig. 2, a side view of the plug of the charging-orifice, and Fig. 3 a top view of this plug.

Similar reference-numerals designate like 25 parts in different views.

If a heavy object is quickly lowered with a common hydraulic jack, the fluid impelled by the action of the weight on the ram rises rapidly in the fluid-reservoir, and the air contained therein is greatly compressed between the surface of the fluid and top of the reservoir. In some cases the air is thus compressed to such an extent that the heads or tops of the reservoirs of the most powerful jacks are fractured by the expansive force of the compressed air, but to obviate this danger by means of a 30 vent through which the fluid would flow if the jack were not upright would be inexpedient for reasons that are apparent.

The object of the invention is to afford the air an exit from the reservoir of such a character as to render it unnecessary to close it to prevent the leakage of fluid from the reservoir through the exit or vent and unnecessary 45 to either regulate it or particularly notice its condition whenever the jack is to be operated.

The jack, of which a fragment is shown in Fig. 1, is of a well-known type, the fluid-reservoir being in the ram and head of the jack.

The head 1 is secured on the ram, which is

forced upward with the head by pumping fluid into the ram-cylinder under the ram with a pump contained in the jack. The objects raised and lowered with the jack rest on the top 2 of the head or on a claw attached to 55 the head. When the ram is in its lowest position, the surface of the fluid 3 is near the top 2 of the head, as appears by Fig. 1. The fluid recedes from the top of the head when the ram is raised and approaches it when the 60 ram descends. Hence as the ram descends from its highest position the volume of air between the liquid and top of the head is rendered smaller and smaller until the ram reaches the bottom of the ram-cylinder, when 65 the volume of air is many times smaller than it was at the beginning of the downward movement of the ram. Then if the air cannot escape from the reservoir and a heavy weight has been rapidly lowered with the jack the 70 compression of the air by the action of the weight on the fluid produces an enormous internal air-pressure, which is liable to fracture the head, as above stated.

The peculiar vent by which the object of the 75 invention is effected is preferably formed in the plug of the charging-orifice 4, as it is shown herein. It then consists of a slit or, preferably, a plurality of slits cut in the plug 5, the slit or slits 6 extending into the plug from its 80 exterior and from end to end of the plug, as appears by Figs. 2 and 3. The plug is screw-threaded and engages like a common plug with a thread cut in the margin of the charging-orifice 4, in which the plug fits snugly, the 85 slit or slits extending across and inside of the screw-thread of the plug. These slits are cut with a very thin saw, each being so small that it forms a capillary duct through which air will pass, but through which the fluid used in 90 the jack will not flow. Such a slit differs from any hole that could be drilled through the plug, for it is impracticable, if not impossible, to drill in the plug a hole small enough and long enough to render it capable of performing the 95 functions of one of the slits 6; so while any drilled hole would allow the air to issue from the jack it would not be a capillary duct, but an opening through which the operating fluid of the jack would leak.

A jack provided with the capillary vent described is neither less serviceable nor more troublesome in any respect than a common jack. Although the plug is screwed tightly 5 into the charging-orifice, the vent satisfactorily performs its functions. It allows the air to issue from the reservoir rapidly enough to prevent an excessive air-pressure from being generated in the jack, and in whatever 10 position the jack may be held the vent does not let any of the liquid escape. The heaviest weight which the jack is capable of raising can be lowered rapidly without subjecting the jack to a greater strain than it is designed to bear 15 with safety.

Obviously a slit or slits like one of the slits 6 and capable of performing like functions might be cut in the margin of the charging-orifice instead of in the plug.

20 The benefit derived from this vent is not to be obtained by a loose-fitting plug, because the liquid will leak around such a plug, and besides a loose plug is subject to other objections well known to persons familiar with hydraulic jacks.

Having thus described my invention, what I claim as new, and desire to secure by Letters Patent, is—

1. A hydraulic jack provided with a capillary vent affording an outlet for the air that is compressed in the fluid-chamber by the action of a weight rapidly lowered with the jack.

2. A hydraulic jack provided with a vent comprising a plurality of capillary air-ducts 35 affording an outlet for the air that is compressed in the fluid-chamber by the action of a weight rapidly lowered with the jack.

3. A hydraulic jack having a vent comprising a capillary air-duct extending through the 40 wall of the fluid-reservoir above the operating fluid, and affording an outlet for the air that is compressed in the fluid-chamber by the action of a weight rapidly lowered with the jack.

4. A hydraulic jack having a vent comprising

ing a capillary slit extending through the wall 45 of the fluid-reservoir above the operating fluid, and affording an outlet for the air that is compressed in the fluid-chamber by the action of a weight rapidly lowered with the jack.

5. A hydraulic jack having in the wall of 50 the fluid-reservoir above the operating fluid a plug containing a capillary vent extending through the plug and wall, and affording an outlet for the air that is compressed in the fluid-chamber by the action of a weight rapidly 55 lowered with the jack.

6. A hydraulic jack having in the wall of the fluid-reservoir above the operating fluid a plug containing a vent comprising a plurality 60 of capillary air-ducts, and affording an outlet for the air that is compressed in the fluid-chamber by the action of a weight rapidly lowered with the jack.

7. A hydraulic jack having in the wall of the fluid-reservoir above the operating fluid a 65 plug containing a capillary vent comprising a slit cut in the plug and affording an outlet for the air that is compressed in the fluid-chamber by the action of a weight rapidly lowered with the jack.

8. A hydraulic jack having in the charging-orifice a screw-plug slit from end to end to form in it a capillary vent affording an outlet for the air that is compressed in the fluid-chamber by the action of a weight rapidly low- 75 ered with the jack.

9. A hydraulic jack having in the charging-orifice a screw - plug - slit across the screw-thread and from end to end of the plug to form in it a capillary vent affording an outlet for 80 the air that is compressed in the fluid-chamber by the action of a weight rapidly lowered with the jack.

FRANCIS H. STILLMAN.
